UNITED STATES PATENT OFFICE.

FRANK J. APPELBEET, OF MONTCLAIR, NEW JERSEY.

DISPLAY-CARD FOR BUTTONS AND THE LIKE.

1,310,729.

Specification of Letters Patent. Patented July 22, 1919.

Application filed May 14, 1918. Serial No. 234,550.

To all whom it may concern:

Be it known that I, FRANK J. APPELBEET, a citizen of the United States, and resident of Montclair, in the county of Essex and State 5 of New Jersey, have invented certain new and useful Improvements in Display-Cards for Buttons and the like, of which the following is a specification.

Heretofore it has been customary to sew 10 certain kinds of buttons upon cards, but such buttons are exposed and are liable to be torn off of the card in handling, and when one button has been removed from the stitching the remaining buttons are more or 15 less loose and liable to fall off the card.

The object of my invention is to provide a 20 card or receptacle to contain small articles, such as buttons, for displaying the same in such a manner that they may be readily observed, and wherein the buttons or the like will be securely retained, protected from contamination, and may be readily removed when required.

My invention comprises a sheet or piece of 25 sufficiently thick material, such as cardboard, provided with a desired number of perforations to receive buttons or the like, and provided on one side with a backing sheet and on the other side with a sheet having 30 an opening provided with a transparent protector over said perforations, the buttons or the like being placed in said perforations and the last named sheet with its transparent protector secured to the card so that the 35 transparent material overlies the buttons or the like to retain them in place, to protect them from contamination, and to permit observation thereof.

My invention also comprises novel details 40 of improvement that will be more fully hereinafter set forth and then pointed out in the claim.

Reference is to be had to the accompanying 45 drawings forming part hereof, wherein, Figure 1 is a perspective view illustrating my improved display card, partly completed; Fig. 2 is a perspective view of the finished display card; Fig. 3 is a section on the line 3, 3, in Fig. 2; Fig. 4 is an enlarged 50 detail section on the line 4, 4, in Fig. 3; and Fig. 5 is a partly sectional perspective view illustrating a modification.

In the accompanying drawings the 55 numeral 1 indicates a sheet or piece of material, such as suitable stiff cardboard, paper or the like, provided with a desired number

of perforations 2 suitably spaced apart, adapted to receive buttons or analogous small articles. At 4 is a backing sheet which may be secured along the rear face of the sheet 1, as by a suitable adhesive, to provide a wall for the perforations in said sheet against which wall the buttons or the like may rest. At 4^a is a covering sheet for sheet 1, which is provided with an opening 5 formed in such a position as to disclose the articles 3 when the sheet 4^a is secured upon sheet 1. At 6 is a sheet of transparent material, such as gelatin or the like, secured between the sheets 4^a and 1, over the perforations and articles 3 in sheet 1. The inner face of sheet 4^a may be provided with glue or other adhesive, indicated at 7, whereby the transparent sheet 6 may be secured to sheet 4^a, and whereby the latter may be secured to the stiff sheet 1 along the margin of the sheets 4^a and 1, surrounding the series of perforations 2. In the preferred form of my invention sheets 4^a, 4 will be made in a single piece, capable of being folded in a hinge-like manner at 8, at one edge of sheet 1, the arrangement being such that the perforated sheet 1 may be secured upon sheet 4 with the sheet 4^a having its transparent protector 6 free therefrom in manner illustrated in Fig. 1, ready for the articles 3 to be placed in perforations 2, before closing the sheet 4^a. The display cards may be manufactured in quantity in the manner stated ready for use, whereby the sheet 4^a having the transparent protector 6 will be in proper position for closing upon sheet 1.

With the device arranged as described the buttons or articles 3 may be placed in the perforations 2 of sheet 1, and then the covering sheet 4^a with its transparent protector may be closed upon sheet 1 and over the articles 3 and secured thereto, in manner as illustrated in Fig. 2. The arrangement is such that the feature of having the sheet 4^a connected with sheet 1 in a hinge-like manner is advantageous for completion of the display card, since when the buttons or articles 3 have been placed in the perforations 2 of sheet 1, sheet 4^a may be closed and secured over the latter expeditiously and accurately by the operator, as the hinge connection 8 will facilitate the bringing together of the parts in proper position, whereby cost is reduced, and a nicely finished article will result.

Instead of securing the sheet 4^a with the

- transparent protector 6 to the sheet 1 by means of adhesive or the like, said sheets may be secured together otherwise, as by means of staples, indicated at 9, driven 5 through the several sheets along the appropriate margin of the transparent protector 6 and clenched, as illustrated in Fig. 5, after the buttons have been placed in the perforations or openings 2 of sheet 1.
- 10 Having now described my invention what I claim is:—
- A display card comprising a sheet having perforations to receive articles to be displayed and provided with a backing sheet 15 secured along one face thereof over said perforations, the material of said backing

sheet extending freely therefrom to fold in a hinge-like manner over the first named sheet as a covering sheet, and provided with an opening to expose the perforations in 20 the first named sheet, and a sheet of transparent material secured to the inner face of the covering sheet opposing its opening, said covering sheet and the transparent sheet being secured upon the first named 25 sheet for retaining the articles in the perforations thereof and to display said articles.

Signed at New York city, in the county of New York and State of New York, this 13th day of May A. D. 1918.

FRANK J. APPELBEET
